UNITED STATES PATENT OFFICE.

CARL A. W. BRANDT, OF GREAT NECK, NEW YORK, ASSIGNOR TO THE SUPERHEATER COMPANY, OF NEW YORK, N. Y.

HIGH-PRESSURE WATER-TUBE BOILER.

Application filed October 31, 1924. Serial No. 747,031.

This invention relates to water tube boilers and has particular reference to boilers using high pressures, that is, pressures of 1000 pounds or more per square inch. Its utility, however, is not confined to such high pressure boilers.

The purpose of the invention is to provide an arrangement of a boiler and a superheater particularly adapted for high pressures which shall be inexpensive to manufacture, which is economical in operation and maintenance, and which shall have other advantages pointed out hereinafter.

The invention is illustrated in the drawings herewith in which Fig. 1 shows at the left a central vertical section and at the right an elevation with the nearest wall removed in order to show certain details of the construction; while Fig. 2 shows a section on line 2—2 of Fig. 1.

The general arrangement and construction of the boiler is similar to that shown and described in my co-pending application, Serial No. 747,032, filed October 31st, 1924.

The water tubes 1—1 of the boiler are arranged in two triangular groups, one at the left and one at the right, as viewed in Fig. 1. One side of the triangle in each case lies adjacent to the boiler setting, the apex of 30 the triangle opposite this side lying at the center of the boiler near the top. There is thus left a large combustion space A which has the shape of an inverted V. This combustion space is located above the furnace 2.

The water tubes 1—1 within the triangular spaces extend from side to side of the boiler. They are all parallel and have an upward slope toward the front as viewed in Fig. 1, and toward the left as viewed in Fig.

2. The two ends of each tube are secured to headers 3—3 and 4—4, the former being lower than their corresponding opposite headers whereby the tubes receive the slope spoken of. The sets of headers, as will be seen from an inspection of the drawings, lie in vertical parallel relation. For convenience they are made sectional, the sections being nipped together. The outermost left and right headers (Fig. 1) are extended downward somewhat below the lower points of the triangles and the tubes connecting them form a protective water screen for the furnace walls.

The headers 3—3 are connected to the drum 5 by means of the tubes 6—6, while

the headers 4—4 are secured to the cross-box 7 by means of the tubes 8—8. It will be understood that there is a cross-box on the left (Fig. 1) corresponding to the one shown at the right.

The steam and water drum 5 is connected to the cross-box 7 by means of tubes 9—9.

At 10—10 are shown connections from the upper part of the triangular spaces occupied by the water tubes to the breeching 11 which in turn is connected to the stack connection 12.

The top of the triangular space is closed by the roof 13.

The headers 3^a—4^a lying at the inner tips of the triangular spaces are extended downwardly as shown and at their lower ends are placed short transverse headers 3^b and 4^b. The headers 3^a—3^a and 3^b are connected to the headers 4^a—4^a and 4^b by water tubes 70 similar in every respect to those used in the remaining portion of the boiler. They enclose a rectangular space extending downward into the combustion chamber A, which space is provided for the superheater 14. This superheater may be of any desired construction, the form shown comprising headers 14^a—14^a and 14^b—14^b to which are connected the tubular superheater elements or units 14^c. The headers 14^a—14^a are connected to the steam space of drum 5 by the steam pipe 15. The superheated steam is taken off from the headers 14^b—14^b.

The roof 13 is left open at the center as at 16 and through this opening 16 extend 90 the tubular superheater units. This opening 16 is connected to the breeching 11 by the duct 17.

In the three passages 11, 11 and 17 there are appropriate dampers, 18, 18 and 19 respectively.

The operation of this boiler may be briefly stated as follows. Products of combustion from the furnace 2 and combustion space A flow through the space between the water tubes toward the exits 10—10 and over the superheater elements toward the outlet 16. The free area for gas passage gradually diminishes toward the exits 10—10 substantially in proportion to the shrinkage of the gases as their heat is given up to the boiler surface, so that a substantially uniform gas velocity is maintained.

The relative amount of the gases passing to the exits 10—10 and the exit 16 can be 110

adjusted or altered by means of the dampers, so that the degree of superheat can be readily controlled.

It will be noted that this boiler uses no 5 curved tubes, that the headers are of the simplest conformation, that there is no large and expensive steam drum, that there is not any expensive baffling, and that the superheater is in a location where it can furnish 10 the high degree of superheat demanded by present practice but is nevertheless protected by water cooled surfaces against the intense radiant heat from the furnace and combustion spaces. These are some of the 15 advantageous features of my novel boiler and superheater arrangement.

What I claim is:

1. In a boiler of the class described the combination of a setting, a furnace in the 20 lower part of the setting, boiler tubes extending transversely across the boiler space and arranged in two substantially triangular groups with one side of the triangles against opposite walls of the boiler setting and the 25 opposite point at the upper central part of the boiler space whereby there is defined an inverted V-shaped combustion space above the furnace, a connection from each of the upper outer corners of the triangular spaces 30 to the stack, two parallel spaced groups of transverse tubes extending downward from the inner upper points of the triangles into the combustion space, a group of transverse tubes extending between their lower ends, 35 whereby a generally rectangular space is delimited from the combustion space, and a superheater extending into said rectangular space.

2. In a boiler of the class described the 40 combination of a setting, a furnace in the lower part of the setting, boiler tubes extending transversely across the boiler space and arranged in two substantially triangular groups with one side of the triangles against 45 opposite walls of the boiler setting and the opposite point at the upper central part of the boiler space whereby there is defined an inverted V-shaped combustion space above the furnace, a connection from each of the 50 upper outer corners of the triangular spaces to the stack, two parallel spaced groups of transverse tubes extending downward from the inner upper points of the triangles into the combustion space, a group of transverse 55 tubes extending between their lower ends,

whereby a generally rectangular space is delimited from the combustion space, all of the said boiler tubes being parallel and having an upward slope, and a superheater extending into said rectangular space.

3. In a boiler of the class described the combination of a setting, a furnace in the lower part of the setting, boiler tubes extending transversely across the boiler space and arranged in two substantially triangular groups with one side of the triangles against opposite walls of the boiler setting and the opposite point at the upper central part of the boiler space whereby there is defined an inverted V-shaped combustion space above 60 the furnace, a connection from each of the upper outer corners of the triangular spaces to the stack, two parallel spaced groups of transverse tubes extending downward from the inner upper points of the triangles into 65 the combustion space, a group of transverse tubes extending between their lower ends, whereby a generally rectangular space is delimited from the combustion space, all of the said tubes being parallel and having an 70 upward slope, vertical headers at the ends of said tubes to which they are secured, and a superheater extending into said rectangular space.

4. In a boiler of the class described the 75 combination of a setting, a furnace in the lower part of the setting, boiler tubes extending transversely across the boiler space and arranged in two substantially triangular groups with one side of the triangles against 80 opposite walls of the boiler setting and the opposite point at the upper central part of the boiler space whereby there is defined an inverted V-shaped combustion space above 85 the furnace, a connection from each of the upper outer corners of the triangular spaces to the stack, a damper in each of said connections, two parallel spaced groups of transverse tubes extending downward from the inner upper points of the triangles into the 90 combustion space, a group of transverse tubes extending between their lower ends, whereby a generally rectangular space is delimited from the combustion space, a connection to the stack from said rectangular 95 space, a damper in said connection, and a superheater extending into said rectangular 100 space.

CARL A. W. BRANDT.
